United States Patent Office.

AMBROSE HAZZARD, OF ST. LOUIS, MISSOURI.

Letters Patent No. 97,914, dated December 14, 1869.

IMPROVED CONDENSING-COLUMN FOR STILLS.

The Schedule referred to in these Letters Patent and making part of the same

To all whom it may concern:

Be it known that I, AMBROSE HAZZARD, of the city and county of St. Louis, and State of Missouri, have invented a new and useful Improved Spirit-Condensing Column, of which the following is a full, clear, and exact description, reference being had to the annexed drawing, making a part of this specification, in which—

Figure 1 represents a vertical sectional elevation of my invention.

Figure 2 represents a transverse section at *x y*.

Similar letters indicate like parts.

This invention is an improvement upon the patent of H. G. Dayton, February 16, 1869.

The object of my invention is to provide an apparatus for the more thorough and rapid condensation of the vapors of the still thrown off in distillation.

The flake-stand *A*, figs. 1 and 2, may be fitted directly to the top of the still, and secured by the flange *t*, and through the centre of it is passed a column, *B*, connected with the neck of the still.

Surrounding *B* is a column, *C*, resting on legs, *a a'*, fig. 1, on the bottom *k* of the flake-stand, while a close cap, *m*, covers both *B* and *C*, as shown.

Around *C*, and resting on the bottom *k*, is another column, *D*, which opens, at the top, into a chamber, *R*, which makes a channel entirely around *D*, as shown, and is covered with a close cap, *n*.

From *R* lead numerous pipes, *e e'*, fig. 1, *e e' e'*, &c., fig. 2, connecting with the coil *H* at the bottom of the flake-stand.

By means of the pipe *b* the stand is filled with water, which entirely surrounds the pipes *e e'*, &c., and the enclosed columns, though not brought in direct contact with any of the latter, except *D*, though the dome *n* is covered. This water can be drawn off, as desired, through *d d'*, which are provided with suitable cocks.

At the bottom of *D*, opening, of course, into both *C* and *D*, is a pipe, *p*, which may be connected with

the still, while, from the coil *H*, extends a discharge-pipe, *s*, connected with the receiver.

The flake-stand being filled with water, and the still put in operation, the vapor passes up through *B*, strikes against *m*, then passes down *C*, thence up *D*, till, striking against the dome *n*, it is thrown down, and passing into the pipes *e e' e'*, &c., it enters the coil, and thence is drawn off, in the form of liquid, into the receiver through *S*.

The arrows indicate the course taken by the vapor.

When the vapor has reached the bottom of *C*, the low-wine and fusel-oil may be drawn off through *p*, and again passed through the still, while the high-wine vapors, uncondensed, pass on to the tubes *e e'*, &c., where, being condensed, they are still further cooled by their passage through *H*.

It is evident that the still may be kept working all the time, the process of drawing off the low-wines causing no delay.

By this apparatus I obtain a vastly-increased surface of condensation; am enabled to free the vapors from deleterious substances, in their passage through the condenser, while, at the same time, the conversion of them into a higher grade of wines is kept up without cessation.

The caps *m* and *n* are in close contact, so that the water acts on both.

I do not, of course, claim any originality in surrounding the vapor-column with water, nor in having one column inside of another, since both are well-known devices, in common use;—but

What I do claim as my invention, and desire to secure by Letters Patent, is—

The chambers *B*, *C*, and *D*, tubes *e e'*, &c., coil *H*, water-jacket *A*, and pipe *p*, when arranged in the manner described, for the purpose set forth.

AMBROSE HAZZARD.
